OUTBOARD MOTOR

Robert E. Bourke, New York, N.Y., assignor to McCulloch Corporation, Marine Products Division, Minneapolis, Minn., a corporation of Minnesota

Filed Mar. 11, 1959, Ser. No. 54,932

Term of patent 7 years

(Cl. D71—1)

Fig. 1 is a perspective view showing the rear and one side of an outboard motor showing my new design.

Fig. 2 is a perspective view thereof showing the front and side opposite that shown in Fig. 1.

Fig. 3 is a top plan view of the outboard motor.

Fig. 4 is a front elevational view.

Fig. 5 is a side elevational view.

Fig. 6 is a rear elevational view.

My design for an outboard motor is characterized by the configuration of the top portion of the motor housing in association with the gradually tapering lower portion thereof.

I claim:

The ornamental design for an outboard motor, as shown and described.
